LIQUID DISPENSER FOR A FLOOR TREATING MACHINE

Carroll M. Gantz, North Canton, Ohio, assignor to The Hoover Company, North Canton, Ohio, a corporation of Ohio

Filed Aug. 31, 1964, Ser. No. 81,508

Term of patent 14 years

(Cl. D9—2)

The dominant features of my design reside in the portions shown in full lines.

I claim:

The ornamental design for a liquid dispenser for a floor treating machine, substantially as shown and described.
